(57) **CLAIM**

The ornamental design for a rucksack seat with two water resistant containers, as shown and described.

DESCRIPTION

FIG. 1 is a top, front, left perspective view of the rucksack seat with two water resistant containers in accordance with my design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top view thereof; and,

FIG. 7 is a bottom view thereof.

The broken lines shown in the Figures form no part of the claimed design.
